UNITED STATES PATENT OFFICE

NORTON A. NEWDICK, OF COLUMBUS, OHIO, ASSIGNOR TO THE COLODER COMPANY, OF COLUMBUS, OHIO, A CORPORATION OF DELAWARE

LOADING MACHINE

Application filed January 19, 1927. Serial No. 162,142.

This invention relates to improvements in loading machines, and while the machine is directed generally to the transferring of bulk materials from one point to another, it is specifically designed for use in connection with underground coal mining, for the purpose of transferring loose broken down coal from a working face to suitable cars or conveyors or other removing means placed adjacent to the discharge end of the machine.

The primary object of the invention resides in a machine of this character of a more simplified and efficient design than other machines heretofore proposed for similar purposes, and one which will enable coal or like materials to be loaded at materially lower costs than when hand labor is employed.

A further object resides in a machine which may be readily employed in connection with the so called long wall or modified long wall systems of mining, wherein it is necessary that the machine shall operate within the limited area provided between a solid coal face and an adjacent line of roof supporting props or timbers, the machine being also designed to operate successfully in relatively thin or low coal seams and to this end the machinery has been compactly disposed so that the machine will be of but minimum height.

With these and other objects in view, as will appear as the description proceeds, the invention consists in the novel features of construction, combinations of elements and arrangements of parts hereinafter to be fully described and pointed out in the appended claims.

In the accompanying drawings:

Figure 1 is a plan view of a loading machine constructed in accordance with the features of the present invention, a portion of the gathering conveyor being broken away to disclose the mechanism carried by the base unit of the machine.

Figure 2 is a side elevation of the loading machine,

Figure 3 is a transverse vertical sectional view taken on the plane indicated by the line 3-3 of Figure 1,

Figure 4 is a detail vertical longitudinal sectional view on the line 4-4 of Figure 1,

Figure 5 is a vertical transverse sectional view taken through the forward end of the loading machine and disclosing more particularly the gathering chain construction,

Figure 6 is a plan view thereof, illustrating more particularly the relationship between the chain construction, the drag flights and cutting bits.

Referring more particularly to the drawings, my improved loading machine comprises generally a base unit 1, which in this instance has been formed to rest directly on the floor of a mine so as to slide thereover. It is obvious within the range of the invention to provide the base unit with wheels or other portable elements, if desired, to facilitate its operation and transportation from place to place, depending upon the system of mining utilized, however, for long wall systems the sliding type of base unit has been found to be preferable. Supported by the base unit is a gathering conveyor 2, which comprises an elongated frame including a forwardly and downwardly extending vertically movable gathering portion 3, and a horizontally extending rigid, elevated discharge portion 4, which is arranged above the base unit and is rigidly connected with the vertical side walls 5 of the base unit. The base unit also carries for pivotal swinging movement in a horizontal plane a rear or discharge conveyor 6, which has its forward end supported for turning movement about a vertical axis 7, the latter being disposed immediately beneath the discharge end of the gathering conveyor, so that material handled by the gathering conveyor will be caused to drop upon the discharge conveyor throughout all of the working positions of the latter. In this instance the discharge conveyor has been designed with a view of loading correctly the materials handled thereby into an elongated conveyor system for transferring the coal from the working face to a main entry or gallery where the material is finally discharged into cars arranged in trips and removed from the mines, although it will be understood that if desired the discharge conveyor 6 could deposit coal directly into a mine car rather than employing the elongated conveyor system.

100

In long wall work, however, the conveyor system is preferable due to the difficulty in advancing mine cars along the face of the working.

5 The gathering conveyor at its rear end rotatably supports a driven head shaft 8, and between the sides of the conveyor frame the head shaft has fixed thereon a plurality of sprockets 9, in this instance three in number. Trained over the sprockets 9 are a plurality of longitudinally extending chains 10, which carry at longitudinally spaced intervals a plurality of gathering flights or bars 11. The chains are adapted to operate in 10 longitudinally extending guides carried by the frame of the conveyor 2 and have their forward ends trained over sprockets 12 mounted upon a foot shaft 13, which is journaled in connection with suitable bearings 15 provided at the forward lower end of the gathering portion 3 of the conveyor 2. The conveyor is driven in the directions indicated by the arrows in Figure 2, wherein it will be noted that the flights 11 are caused to directly engage the material deposited on the mine floor, and to elevate such material onto the conveying plate 14 of the gathering conveyor, so that the movement of the flights in the rearward direction indicated will cause 20 the material to traverse the full length of the gathering conveyor and to be finally deposited upon the discharge conveyor 6. The flights 11 are preferably located in the relatively offset or staggered manner shown in 25 Figure 1, so that the operation of the gathering conveyor will be more continuous in its action on the coal and at the same time the double flights will permit of a stronger conveyor construction than if the flights were 30 extended the full width of the conveyor frame. The ends of the flights may be provided with cutting bits 15, if desired, and also the upper edges of the flights may be provided with teeth as at 16 so as to facilitate 35 the entrance of the flights into the coal pile and to increase their gathering and disrupting capabilities. The forward lower end of the conveyor 2 is provided with a supporting shoe 17, which rests directly on the mine 40 floor to the rear of the foot shaft 13 and serves to facilitate the sliding of the machine over the floor but does not interfere with the gathering action of the conveyor. It will be noted that all parts of the machine which engage 45 the coal deposited on the mine floor are movable parts, and all forwardly projecting wedges, plates and other inclined members provided on machines of this character heretofore proposed have been eliminated. By 50 this construction I have produced a greatly improved gathering action and have minimized the resistance which the coal offers to the advancement of the machine into and under the coal pile.

55 In this instance the gathering conveyor

has been shown as being rigidly mounted in an inflexible manner on the base unit. It is, however, within the scope of the invention to permit the gathering conveyor or the forward portion thereof to swing vertically if desired, whereby the front end of the machine will be enabled to conform to irregularities in the floor surface.

60 Mounted upon the forward part of the base unit is a motor bed 18 which supports a motor 19 of any suitable type, such for example as the ordinary electric or compressed air driven motors commonly found in mining equipment. The operating shaft 20 of the motor enters a speed reducer 21 by means of which a cross shaft 22 is driven from the motor at a relatively reduced rate of speed as regards the shaft 20. Slidably keyed to the outer end of the shaft 22 is a clutch 23, which is adapted to be thrown into or out of engagement with a clutch face provided upon the hub of a sprocket 24 which is loosely rotatable on the shaft 22. A chain is passed over the sprocket 24 and over an aligned sprocket 25 provided on a stud shaft 26, extending horizontally from one side of the gathering conveyor frame and mounted in a 65 casing 27. Also, rotatable with the sprocket 25 is a companion sprocket 28, over which is passed a chain 29 which leads to a sprocket 30 provided upon the head shaft 8 of the gathering conveyor. By this arrangement the motor 19 is employed to drive the conveying means of the conveyor 2, and through the medium of the clutch 23 the operation 70 of the gathering conveyor may be stopped without arresting rotation on the part of the motor.

75 To feed the machine forwardly into the coal or other material to be gathered the shaft 22 is provided with a sprocket 31, formed to rotate with said shaft, and over this sprocket there is passed an endless chain which drives a registering sprocket 32 fixed to a countershaft 33, journaled in connection 80 with the base unit below the stud shaft 26. Fixed upon one end of the shaft 33 is a sprocket 34 over which is trained an endless chain which leads to a sprocket 35 mounted on a drum shaft 36 so as to rotate in unison 85 with this shaft. Loosely mounted upon the shaft 36 is a pair of drums 37 which may be selectively driven individually or as a unit by means of sliding clutch members 38, keyed to said shaft and which may be manually 90 operated, through any suitable link arrangement to engage with clutch faces or jaws formed with the drums 37.

95 Connected with the drums 37 are draw chains 39 which are trained rearwardly as indicated, and are passed around guide wheels 40, carried by the base unit, and are then trained forwardly, having their extreme forward end united with jacked anchors 41, which are set up between the mine floor and 100

roof. Thus, by means of this construction, when it is desired to feed the machine into the coal, the clutch members 38 are both engaged with the clutch jaws of said drums and the 5 motor is started so that through the power transmission device the drums will be enabled to rotate slowly and powerfully. The wrapping of the chains 39 about the drums shortens the effective lengths of said chains 10 and consequently there is imparted to the machine a relatively slow but powerful forwardly directed sumping movement. This construction in connection with the peculiar features of design of the gathering conveyor enables the machine to gather coal effectively 15 and at a rapid rate of speed so as to produce a machine having a relatively high loading capacity with simple yet practical features of design. The drums 37 may be selectively operated so as to swing the gathering conveyor 20 bodily to the right or the left, enabling its forward end to be positioned to the best advantage in relation to the material to be gathered.

25 In operation the machine is alternately moved forwardly and rearwardly so that the coal face may be attacked over the entire width thereof and the retractive movement thereof is accomplished by the provision of 30 a single drum 42 located on the shaft 36 between the drums 37. The hub of the drum 42 is provided with a sprocket 43, over which is trained an endless chain which leads to a larger sprocket 44 loosely mounted on the 35 shaft 33. The sprocket 44 is provided with a clutch face adapted for engagement with a sliding clutch member 45 keyed to the shaft 33. Obviously, by rotatably connecting the sprocket 44 with the shaft 33 through the 40 medium of the clutch member 45 rotary motion may be imparted to the drum 42, which is loosely mounted on its supporting shaft 36. Since the retraction of the machine offers no unusual resistance, except the mere weight 45 of the machine, the retractive movement may be performed at a higher rate of speed than the forward sumping movement, and the sprocket sizes have been proportioned to include this feature. For purposes of simplicity it has not been deemed necessary to illustrate the manually operated levers for actuating the clutch members 23, 38 and 45, since it will be understood that any suitable 50 manual control may be utilized in this connection.

55 The discharge conveyor comprises a substantially straight trough shaped frame 46 having a driven head shaft 47 journaled at the outer or discharge end thereof and a foot shaft 48 at the inner end, the latter being disposed beneath the discharge portion 4 of the gathering conveyor. The shafts 47 and 48 are provided with sprockets around which are trained longitudinally extending trans- 60 versely spaced chains 49, which are connect-

ed by transversely disposed flights 50. In the discharge conveyor the flights extend across the full width of the frame 46, and are not shortened or staggered as in the case of the gathering conveyor, since the service to which the flights are placed is considerably lighter and the added strength is not needed. The flights 50 advance as indicated by the arrows in Figure 2 and move over the bottom 51 of the frame 46, advancing the material engaged thereby rearwardly and longitudinally of the frame. The extreme rear end of the conveyor 6 is adapted to overhang a mine car or other additional conveyor means into which the materials are discharged and removed from the working face for loading purposes.

25 The head shaft 47 of the discharge conveyor is driven by a motor 52 suspended from the bottom of the frame 46. The shaft of the motor 52 extends into a gear reduction unit 53, and this unit drives a sprocket 54 located on one side of the frame 46. Rotatable with the sprocket 54 is a second sprocket 55 over which is passed a chain 56 leading to a 30 sprocket wheel 57 fixed on the head shaft 47. By this construction an independent drive is provided for the delivery conveyor which will enable the same to operate throughout its entire range of horizontal swinging movement.

To permit of the support and swinging movement of the delivery conveyor, the forward part of the frame 46 is provided with a 35 bed plate 58 from the center of which projects downwardly a stud shaft 59, constituting the axis 7. The plate 58 is formed to receive a thrust bearing 60, which is mounted upon a pedestal casting 61 arising from the base 1. The casting 61 is also provided with 40 an anti-friction bearing 62, vertically spaced from the bearing 60 so as to facilitate the horizontal swinging movement of the discharge conveyor. The casting 61 is provided with a curved opening 63 through 45 which passes the rearwardly extending chain 64 leading from and connected with the central drum 42. The rear end of the chain 64 extends beyond the delivery conveyor and is connected with a post or jack 65, which serves 50 as an anchor, whereby when the drum 42 is actuated to wind the chain 64 thereabout the machine will be drawn rearwardly and into a more advantageous position to attack the materials to be loaded. To further assist in the 55 swinging support of the discharge conveyor the under side of the discharge portion 4 of the gathering conveyor is provided with a wear plate 66, which is engaged by a plurality of rollers 67 mounted in connection with 60 brackets 68 secured to the front end of the discharge conveyor. The rollers 67 help to sustain the weight of the rear overhanging end of the delivery or discharge conveyor, 65 permit of the free turning movement of said 66.

conveyor and eliminate the necessity of employing supporting means between the rear portion of the conveyor and the mine floor. It will be understood that the jack 65 may be positioned wherever desired in relation to the rear end of the machine so as to facilitate its positioning in relation to the pile of material to be attacked.

In view of the foregoing it will be seen that the present invention provides a loading machine of simple yet efficient construction for the loading of coal and like materials in underground mines. The construction of the machine permits of its use in mines having thin coal seams and where the overhead room is limited, for example, in coal having a seam of approximately 36 inches in thickness, the machine being constructed to provide for adequate lump clearance between the highest point of gathering conveyor and the roof of the mine in a seam of the dimensions given. This clearance is provided in part by mounting the conveyors on a sliding frame, where wheels have been eliminated and also in part by reason of the construction and arrangement of the driving mechanisms. Further, the machine is admirably suited for loading under the long wall system of mining, in which event the machine will move parallel to the face of the mine, between said face and the row of supporting props placed adjacent thereto. The width of this space is limited ordinarily to about five feet and consequently the width of the machine has been proportioned accordingly and the frontal attack method of gathering used. The forward section of the gathering conveyor is pivoted for swinging movement about a horizontal axis 70 in order that the front end of the gathering conveyor may be elevated to a position clear of the floor when the machine is being transported from place to place. A simple structure for effecting the elevation of the forward section consists, as shown in Figure 2, of a pair of toggle levers 71, pivotally secured to the gathering conveyor and the base 1. A cable 72 is connected with the pivoted meeting portions of the toggles and passes around a reel or drum 73 carried in connection with the speed reducer 21. When the toggles are in their elevated positions supporting the gathering conveyor above the floor the same are off center and thereby locked by the weight of the gathering conveyor against movement, although this locked condition is insured by the connection of the cable 72 with the drum 73. It will be observed that the bits 15 overlie the chains 10, as shown more particularly in Figures 5 and 6. These bits provide a movable disrupting force immediately over or in front of the chains so that the advance of the machine into the coal will not be obstructed in any manner and practically the entire width of the gathering conveyor may thus be employed effectively in

the gathering and disrupting of the coal. While I have shown jaw type clutches for governing the operation of driving and driven parts, such as have been indicated by the numerals 23 and 36 and at 73, nevertheless it will be understood that friction plate clutches may be substituted to secure greater flexibility and ease and control in operation, and that such friction types of clutches are the full equivalents of the jaw type clutches 75

While I have described what I consider to be the preferred form and construction of a loading machine for accomplishing the results stated, nevertheless it will be understood that various changes and departures may be made in the construction from that herein specifically shown and described without departing from the spirit and substance of the invention as the latter is set forth in the subjoined claims.

What is claimed is:

1. In a loading machine, a portable base unit, a gathering conveyor connected with said base unit, a delivery conveyor carried by said base unit and having the forward portion thereof arranged beneath the discharge end of said gathering conveyor in receiving relation with respect thereto, a pedestal casting arising from said base unit, a vertical shaft carried by said delivery conveyor and turnable in said casting, said casting being provided with a guide opening, a motor driven reel mounted on said base unit and the cable connected with said reel and extending rearwardly from the base unit through the guide opening provided in said pedestal casting, the rear end of said cable being connected with a rearwardly disposed anchor mounted independently of said machine.

2. In a loading machine, a base unit, a delivery conveyor, a vertical pivotal connection between the forward part of said delivery conveyor and said base unit permitting said conveyor to swing in a horizontal plane, the rear end of said delivery conveyor being disposed in overhung relationship with respect to said base unit, a motor, and power transmission means carried by the overhanging end of said delivery conveyor, and a plurality of anti-friction rollers carried by the forward end of said delivery conveyor and engaging a rigid surface formed with said base unit to sustain the weight of the overhanging end of the conveyor.

3. In a loading machine, a base unit, a gathering conveyor carried by said base unit including three transversely spaced longitudinally extending endless chains, head and foot shafts carried by the ends of said gathering conveyor and provided with sprockets over which said chains pass, a motor, power transmitting means between said motor and said head shaft, and a plurality of flights 130

connected with said chains and movable in unison therewith, the flights on one side of said conveyor being disposed in staggered or offset relationship with respect to the flights carried by the other side of said conveyor.

- 5 4. In a loading machine, a portable base unit, a gathering conveyor including an elongated frame provided with a forwardly and downwardly extending front portion arranged in advance of said base unit and disposed to engage with the mine floor, transverse head and foot shafts carried by the ends of said frame and provided with sprockets, at least three transversely spaced longitudinally extending endless chains trained over said sprockets, and a plurality of transversely extending flights having the ends thereof connected with an adjacent pair of chains, said flights being disposed in staggered or offset relationship with respect to complementary flights carried by the next adjacent pair of laterally disposed chains.

- 5 5. In a loading machine, a base unit, a gathering conveyor carried by said base unit formed to include an elongated frame provided with a forwardly and downwardly extending portion arranged in advance of said base unit with its forward end adapted to engage with the mine floor, at least three longitudinally extending transversely spaced chains carried by said gathering conveyor and movable in substantially vertical planes, and a plurality of transversely extending longitudinally spaced flights arranged in sets having the ends thereof connected with an adjoining pair of chains for movement in unison therewith, one of said chains being connected with adjoining sets of flights, the flights of one set being disposed in offset relationship with respect to the flights of adjoining sets.

6. In a loading machine, a forwardly and downwardly inclined gathering conveyor having the forward end thereof adapted to rest on the mine floor, three or more longitudinally extending transversely spaced chains carried by said gathering conveyor and movable longitudinally thereof and having upper and lower runs, guide means for maintaining said chains in transversely spaced relation, a plurality of short transversely extending flights having their ends rigidly connected with adjoining pairs of said chains, said flights being arranged to project in advance of the gathering conveyor at the forward and lower end of the latter to directly attack the material to be loaded, and a plurality of cutting bits carried in connection with said flights and chains adjacent to the ends of said flights and having the cutting edges thereof disposed to project over the outer chains in the upper run.

In testimony whereof I affix my signature.

NORTON A. NEWDICK.
